CLAIM

The ornamental design for the boat shaped wagon, as shown and described.

DESCRIPTION

FIG. 1 is a front perspective view of a boat shaped wagon showing our new design;

FIG. 2 is a front perspective view thereof; the opposite side being a mirror image;

FIG. 3 is a top plan view thereof;

FIG. 4 is a rear plane view thereof;

FIG. 5 is a left view with flip-up top with the handle in a secured upright position thereof; the opposite side being a mirror image;

FIG. 6 is a front view with flip-up top thereof;

FIG. 7 is a bottom plan view with the handle in a fold-under position thereof; and,

FIG. 8 is a top elevational view thereof.

The following elements have not been shown in all views for ease of illustration only: the top in FIGS. 2,3 and 4, the grip in FIGS. 1 and 2, the handle in FIG. 3 and the straps in FIGS. 1 and 2.
